PERPETUAL CALENDAR

Alfe Patterson, Spokane, Wash.

Application September 30, 1946, Serial No. 700,215

1 Claim. (Cl. 40—115)

1

This invention relates to an improved type of perpetual calendar.

It is an object of this invention to provide a mechanical calendar which may be used to indicate the calendar month and date of any month in any year.

Another object of this invention is to provide an improved mechanical calendar for use in indicating any month in any year whereby the changing of the calendar may be readily accomplished by movement of but a single handle.

Still another object of this invention is to provide an improved mechanical calendar having a sliding date plate or card and a sliding cover plate for blanking from view the dates not applicable to the selected month, wherein the calendar is so constructed and arranged that sliding movement of the cover plate or card will effect sliding movement of the date plate after the cover plate has moved a certain distance independent of the date plate.

Yet another object of this invention is to provide a mechanical calendar of the kind to be more particularly described hereinafter, which is constructed with a minimum number of parts and which may be readily operated with a minimum of instructions.

A further object of this invention is to provide a mechanical calendar of this kind which may be readily constructed and manufactured with a minimum amount of labor and which is particularly adaptable to mass production methods of construction.

With the above and other objects in view, my invention consists in the arrangement, combination and details of construction disclosed in the drawing and specification, and then more particularly pointed out in the appended claim.

In the drawings,

Figure 1 is a top plan view, partly broken away, of my mechanical calendar.

Figure 2 is a vertical section taken on the line 2—2 of Figure 1.

Figure 3 is a top plan view of a modified form of my invention; and

Figure 4 is a bottom plan view with the rear cover removed.

Referring to the drawings, in Figures 1 and 2, the numeral 10 designates generally a mechanical calendar constructed according to an embodiment of my invention. The calendar 10 is constructed with a face plate 11, a date plate 12, a cover plate 14, and an indicator 15, pivotally connected together by a pivot pin or rivet 16, which plates may be made of metal, plastic, paper, or other suitable material.

The face plate 11 is formed of a rectangular sheet of material and is formed substantially midway along the length thereof with a seg-

2

mental arcuate cut-out portion 17, having radially disposed side edges, which extend divergently outward from the pivot 16 midway along the lower side edge of the plate 11. An elongated segmental arcuate slot 18 is formed through the plate 11 inwardly of the cut-out 17 and a second elongated segmental arcuate slot 19 inwardly of the slot 18.

A segmental arcuate date plate 12 is pivotally connected to the face plate 11 by pin 16, whereby the plate 12 may slide relative to the face plate 11 about the pivot pin 16. The date plate 12 is provided on its upper surface with numerical indicia arranged in six concentric segmental arcuate tiers or series, and with the numbers in adjacent tiers disposed in radially extending columns converging at the pivot point 16. The first or uppermost series includes numbers 1 to 7, the second series numbers 2 to 14, the third 9 to 21, the fourth 16 to 28, the fifth 23 to 31, and the sixth the numbers 30 and 31, the numbers in each series increasing arithmetically from left to right and the series so arranged that the last numbers in the first four arcuate series are radially aligned and the first numbers in the second to the last series are radially aligned. The opening 17 in the face plate 11 is such as to expose for viewing a complete month of numbers on the date plate 12, or in other words, is of such a size to expose seven spaces in each series in such a manner that the numbers increase from left to right in lower series as in a regular calendar month. The numbers are so arranged that the numbers in each radial column increase by seven inwardly toward the pivot 16.

A segmental arcuate cover plate 14 is pivotally mounted between the face plate 11 and date plate 12 on the pivot 16 for covering certain selected numbers in the cut-out portion 17 so that the numbers visible will correspond to the number 35 of days in the selected month. The plate 14 is formed with a segmental arcuate outer edge of sufficient length to cover at least three numbers or spaces on the left side in the fifth series and a reduced radius portion or notched edge for covering the numbers in the sixth series.

The pointer or indicating arm 15 is pivotally mounted on the pivot pin 16 and is provided with a knob or handle 20 fixed on its upper side whereby an operator may move the indicator with his fingers. The indicating arm 15 is fixed relative to the cover plate 14 by a rivet 21 which extends through the arcuate slot 19 and is slidable therein so that movement of the indicator arm 15 over the face plate 11 effects sliding of the cover plate 14 relative to the face plate 11.

The cover plate 14 is further formed with a short segmental arcuate slot 22 in which a pin 24 fixed to the date plate 12 may slide. The slot

3

22 is of a length equal to three radial columns so that when the cover plate 14 is moved that distance further movement thereof will effect sliding movement of the date plate 12, together with the cover plate 14 relative to the face plate 11.

The legends Mon to Sun are fixed on the face plate 11 reading from left to right in radial alignment with the radial columns of numbers for indicating the days of the week, and sliding of the date plate 12 will align the numbers with the selected week day for the certain month desired. The slot 18 in the face plate 11 extends a distance equal to the angular distance of ten radial columns, starting from the left column of numbers on the date plate 12, and indicia, as A to G, starting from the fourth column are fixed on the face plate 11. Indicia as Roman numerals I to IV are inscribed on the cover plate to be viewed through the slot 18 and correspond to the first four columns on the date plate 12.

By moving the pointer 15 to register with a selected letter on the face plate 11, the date plate 12 is moved to align the numbers thereon with certain week days and returning the pointer 15 to align a certain Roman numeral with the selected letter moves the cover plate 14 back to cover the last days in the month which should not appear for that certain month.

A chart or key is provided for determining the position of the pointer for any desired month, and may be attached to the face of the calendar 10 as shown in Figure 1. The key in Figure 1 is calculated for a period of time extending from 1936 through 1956.

In the use and operation of this calendar 10, when a certain month is selected to be shown, the key letter is determined from the key or chart and the indicator 15 moved into alignment with that letter on the face plate 11. The key Roman number for that month is determined, and the indicator 15 is moved back to align that number with the selected letter, whereupon the month for that date is shown in the aperture 17. The number key is to determine the number of days in the month and is as follows:

- I February (28 days)
- II February in Leap Years (29 days)
- III April, June, September, November (30 days)
- IV January, March, May, July, August, October, December (31 days)

As an example to show the month of January 1946, on the key, corresponding to January in the vertical column and 1946 in the horizontal column, the letter B is found. The handle 15 is moved clockwise to the letter B, whereupon the cover plate 14 exposes all the numerals on the date plate 12 and the numbers 1, 8, 15, 22 and 29 are in the radial column under the day of Tuesday. As January has 31 days, the numeral IV is selected and the pointer 15 moved back to IV which still leaves 31 days exposed on the calendar 10.

As another example, to show the month of February 1948. The key letter G is found on the key chart. The indicator 15 is moved first to G and back 2 spaces (II) thereupon moving the cover plate 14 to cover the numerals 30 and 31, exposing only 29 days.

In Figures 3 and 4, there is exemplified, a modified form of this mechanical calendar. The modified calendar 30 is formed of sheets of relatively stiff paper, as an envelope, though other materials may be used. The calendar 30 is 75

4

formed of an envelope 31 having a front sheet or plate 32 and a rear sheet or plate 34. A date plate or sheet 35 is pivotally mounted on the front sheet or plate 32 by a pivot pin 36, and a cover sheet or plate 37 is pivotally mounted between the front plate or sheet 32 and the date sheet 35. The cover plate or sheet 37 is provided with a strap or band 38 engaging about the rear side of the date plate 35 with the connections of the strap 38 and plate 37 spaced from the edges of the plate 35 in certain positions, so that the corner of the strap 38 may engage the sheet 35 upon movement of the cover plate 37 for sliding the date plate 35.

15 The front plate 32 is formed with an opening 39 similar to that of the first form as opening 17 and is covered with a transparent sheet 40.

An indicator and handle 41 is fixed at its inner end by means of an adhesive or the like to the top of the sheet or cover plate 37, the front end thereof extending through an arcuate slot 42 in the front plate 32.

20 Key letters A to G are inscribed or printed on the front side of the front plate 32 and three marks as lines 44 precede the letters and are spaced apart a distance equal to the spacing of the letters A to G and the columns of numbers on the date sheet or plate 35.

25 The arcuate outer edge of the sheet 35 is notched as at 45 intermediate the length thereof to provide outwardly extending stops 46 at each side of the sheet 35, which are engageable with the stop bar 47 for limiting the travel of the plate 35 in either direction. The stop bar 47 overlies the edge of the notched side 45 and acts somewhat as a brake to hold the date sheet 35 against sliding until the bumper 48 fixed in the corner formed by the strap 38 and cover plate 37, engages in the notch 49 in the side of the sheet 35, whereupon the indicator 41 and sheets 35 and 37 will be moved in unison.

30 The procedure for the use of the calendar 30 is the same as that for the calendar 10. While no Roman numerals are shown on the calendar 30, the pointer 41 is moved back a certain number of spaces to cover the last days of the month not required.

35 The arcuate edge of the plate 37 is notched twice as at 50 and 51, the second notch 51 being necessary only to provide a plate 37 of a width greater than that of plate 35 so the plate 35 may be disposed between the edges of the plate 37 for the reasons set forth above.

40 When no Roman numerals are affixed on the calendar, the correct spacing for moving the pointer back to cover the last days of the month may be figured from the following:

45 February, 28 day month, return pointer 3 spaces from key letter;
February, 29 day, return pointer 2 spaces;
April, June, September and November, 30 days, return pointer 1 space;
January, March, May, July, August, October and December, 31 days, do not return indicator.

50 The use and operation of the modified calendar 30 is the same as that for the calendar 10.

55 The chart for key letters, shown on Figure 1, is applicable only for the years 1936 to 1956, though the calendars may be used for other dates.

60 For any month between 1700 AD and 1999 AD, the following chart may be used, the chart on Figure 1 being only a small section thereof. The years after 1752 are in the Gregorian calendar and those before 1752 are in the Julian calendar. Not all of the countries made the change in 1752.

I do not mean to confine myself to the exact details of construction herein disclosed, but claim all variations falling within the purview of the appended claim.

What I claim is:

A perpetual calendar of the kind described comprising a front face plate, a rear date plate, a segmental arcuate cover plate between the rear plate and front plate, an indicating arm fixed relative to said cover plate, a pivot pin pivotally connecting said plates together for pivoted movement one relative to the other, segmental arcuate series of numerical date indicia on said date plate concentric to said pivot pin, the numbers of said series increasing as the series approach said pivot, said face plate formed with an enlarged segmental arcuate opening for exposing certain columns of said series exposing the dates of a selected month, said cover plate having a notched peripheral edge for overlying certain selected ones of said indicia of said exposed series immediately adjacent said pivot, said cover plate formed with a segmental arcuate slot therein, a pin fixed on said date plate engaging in said slot providing a lost motion connection between said date and cover plates whereby said date plate may be pivoted relative to said face plate after initial pivoting of said cover plate, indicia on said cover plate perceptible through a segmental arcuate opening in said front plate, indicia on said front plate adjacent the latter opening

therein, the indicia on said face plate being correlated with a chart for determining the proper positioning of said series in the enlarged opening in said face plate, whereby pivoting said date and cover plates for registering said indicator with a selected one of the indicia on said face plate will properly position said series in said enlarged opening and said cover plate may be pivoted in a reverse direction for covering selected ones of the series immediately adjacent said pivot.
